UNITED STATES PATENT OFFICE.

JAMES D. McLEOD, OF FLINT, MICHIGAN.

LIGHT ATTACHMENT FOR GUNS.

1,330,885.

Specification of Letters Patent. Patented Feb. 17, 1920.

Application filed January 23, 1918. Serial No. 213,360.

To all whom it may concern:

Be it known that I, JAMES D. McLEOD, a citizen of the United States, residing at Flint, in the county of Genesee, State of Michigan, have invented certain new and useful Improvements in Light Attachments for Guns; and I do hereby declare the following to be a full, clear, and exact description of the invention, such as will enable others skilled in the art to which it appertains to make and use the same.

This invention relates to illumination and particularly to attachments for guns for projecting light to a distance.

15 The principal object of the present invention is to provide a novel and improved searchlight for a gun which is especially adapted to be used on airships or as anti-aircraft means.

20 Another object is to provide a device of this character by means of which a large beam of light can be thrown in an effort to locate the enemy, and which can be adjusted to focus a smaller beam of light on 25 the enemy when located.

Other objects and advantages will be apparent from the following description when taken in connection with the accompanying drawing.

30 In the drawing:

Figure 1 is a side elevation of a gun equipped with my invention, the light device being in the position desired when searching for the enemy.

35 Fig. 2 is a side elevation of the gun and invention applied thereto, the latter being in the position for firing at the enemy.

Fig. 3 is a vertical longitudinal sectional view through the device, the gun being in 40 elevation.

Fig. 4 is a vertical transverse sectional view taken on the line 4—4 of Fig. 3.

Referring particularly to the accompanying drawing, 10 represents a gun stand and 45 11 the gun mounted thereon. The gun shown is of the type known as anti-aircraft guns. Mounted on the barrel of the gun, and extending the length thereof, is a channeled guide 12 preferably semi-circular in cross section and in the outer end of which is suitably secured the outermost section 13 of a telescoping tube. While this section 50 may be secured in any suitable means, its

forward end in Fig. 3 is shown as supported at a little distance above the bottom of 55 the guide 12 by means of a post 12' rigidly connecting the two elements. The section 13 has engaged thereon a slightly larger section 14, and onto the rear end of this section 14 is telescoped the rearmost section 60 15. In the rear end of the section 15 there is secured a lamp casing in which is mounted a strong searchlight lamp 16, which is of a size to fit closely in the guide 12 along which it can be adjusted by hand. In front 65 of the lamp 16 there is mounted a lens 17.

When the sections of the telescoping tube are in the position of Fig. 1, the beam of light projected from the lamp, through the lens will be of considerable diameter, 70 whereby a large field of vision is produced in the sky to search out enemy aeroplanes. When the enemy has been located, the tube is extended to the position of Fig. 2, when the beam of light will be greatly reduced 75 and a comparatively smaller one formed to be concentrated on the enemy machine. The gunner then proceeds to fire the gun until the enemy is hit, while at the same time swinging his gun on the stand, to follow the movements of the enemy plane. 80

There is thus provided a novel and efficient device whereby the sky can be easily and thoroughly searched for enemy machines, and when the enemy has been located 85 the size of the beam of light can be reduced while at the same time the intensity thereof will be increased and directed at the enemy for the gunner to fire and attempt to bring 90 the enemy down.

While I have shown and described the searchlight as used in connection with an anti-aircraft gun, it will be readily understood that the device is as readily applicable to guns used on aeroplanes or other types 95 of aircraft, for locating the enemy on the ground and directing fire against him.

What is claimed is:

The herein described searchlight attachment for guns, the same comprising a channeled guide adapted to be mounted upon and along the gun barrel, a post rising from its bottom at its front end, a telescopic tube including a small section whose front end is supported by said post, a larger section 105 slidable over the rear end of the smaller sec-

tion, and a rear section slideable over the rear end of the second section and along the bottom of the guide, a lamp casing communicating with the rear end of the rear section, a source of light therein, and a lens in the casing forward of said source, the whole for use substantially as set forth.

In testimony whereof I affix my signature in the presence of two witnesses.

JAMES D. McLEOD.
